UNITED STATES PATENT OFFICE.

FERNANDO ARENS, OF SAO PAULO, BRAZIL.

MACHINE FOR THE MANUFACTURE OF PIPING AND THE LIKE BY CENTRIFUGAL CASTING.

Application filed March 27, 1923. Serial No. 626,141.

To all whom it may concern:

Be it known that I, FERNANDO ARENS, a citizen of Brazil, and a resident of Sao Paulo, Rua Libero Badaro 120, Brazil, have invented certain new and useful Improvements in Machines for the Manufacture of Piping and the Like by Centrifugal Casting, of which the following is a specification.

10 The invention relates to machines for the manufacture of hollow articles, especially piping, by centrifugal casting.

A preferred embodiment of the machine is illustrated by the drawings, Fig. 1 being 15 a longitudinal section, showing the parts in their relative position at the commencement of the operation; Fig. 2 is a similar view, with the parts at the end of the forward movement; Fig. 3 is a similar view of 20 the machine after the parts have been returned to the initial position, the finished pipe having been removed; Fig. 4 is a section as in Fig. 1 enlarged, the section being taken substantially upon the line C—D of

25 Fig. 5, looking in the direction of the arrows; Fig. 5 is a section taken upon the line A—B of Fig. 4; Fig. 6 is a front view of the core; Fig. 7 is an enlarged longitudinal section through the casting tube; 30 and Fig. 8 is a section taken upon the line E—F of Fig. 7, looking in the direction of the arrows.

Upon the base 4, which rests upon the general support 3, is revolvably mounted by 35 means of shaft 4, the casting tube 6. Upon the same base 4 is supported a metal container 1. The metal container rests upon insert rings 28 (Fig. 7), the number of which regulates the pressure of the liquid 40 metal. The bottom ring 28 rests directly upon the casting tube 6. A stopper 2 that may be removed at will and replaced by another stopper, controls the flow of molten metal from the container 1 to the tube 6.

45 The casting tube 6 consists of an outer wall 29 and a number of various insulating layers 30. When the stopper 2 is lifted, the molten metal from the container 1 enters the tube 6, flowing against the insulating 50 layers 30.

At the other end of the base 3 (Fig. 1), there is a second support 7 having a socket. A mandrel 9 having a tenon 8 is rotatably mounted in the socket and is supported upon rollers 10 that rest upon a swivel plate 11.

The mandrel may be lifted by hydraulic pressure supplied to the socket below the tenon 8 through a pipe 27. The mandrel is counterbalanced at the rear end by a balance weight 12. A weight 13 similarly 60 counterbalances the casting tube 6.

The casting tube projects into a casing 14 in which is disposed an electrically driven 65 rotary casting mould 15 in co-axial relation to the casting tube 6. The mould 15 contains a spiral 16 and is closed by a core 18.

The core 18 (Fig. 6) consists of several segments 37 separated by slits into which strips 45 of soft wood or the like are inserted, which, under the influence of the 70 pressure and the heat of the pipe-head, shrink and char. The segments 37 are held together by springs 38 (Figs. 4 and 6) which form a resilient union. Under the slits are arranged movable plates 36, which 75 support the inserted strips. The plates are attached at one side to one segment and extend across the slits in sliding contact with the adjacent segment.

The cylinder is driven by an hydraulic 80 press 19 (Fig. 1). At both ends of the casing 14 there are ramps or cams 21 and 22. These ramps rise sharply, and then pass into the horizontal. At one end of the press 19 is a throttle valve 42 for controlling the 85 inflow and outflow of the pressure fluid.

At the sides of the cylinder are disposed cooling water pipes 43. In order to remove the fumes or gases formed in the cylinder, suction devices, like ventilators, may be 90 provided. The piston 20 (Fig. 2) is connected to the front end of the casing 14 by means of a connecting arm 23. This piston is hollow in order that the cooling water may pass therethrough and the hollow connecting arm 23 to the tubes 43. To facilitate the movement of the cylinder, it runs upon rollers 24 along guides or tracks 25. The 95 operation is as follows:

The parts are shown in their initial position in Fig. 1. The casing is at this time at the left of Fig. 1. The motor 31 is now started causing the casting mould to revolve. At the same time the stopper 2 is lifted and water under pressure is admitted 100 to the press 19. The molten metal flows from the container 1 into the tube 6 and water under pressure is at the same time admitted through the pipe 44 into the press 105 19, causing forward movement of the casing 110

14. Its movement may be regulated by the throttle valve 42. The molten metal flows out from the outlet head 26 of the casting tube 6 into the head of the casting mould, 5 the latter meanwhile rotating about the horizontal axis. A differential 33 is arranged between the electric motor 31 and the drive 32 of the casting mould, and is adjustable for various speeds by means of 10 the lever 34. As the mould thus moves forward while rotating, the pipe 17 is cast by centrifugal action. The quantity of molten metal admitted at each operation into the container 1 corresponds to the amount required 15 for the making of one pipe. Toward the end of the forward movement of the cylinder, the water is automatically almost entirely shut off by the ramp 22. The movement is thus slowed down at the end of the 20 stroke so that the casing is brought to a stop without shock. Meanwhile the mandrel 9 has become projected into the interior of the pipe just solidified (Fig. 2). Now by admitting water under pressure by way of 25 the pipe 27, the mandrel 9 may be lifted until the pipe 17 hangs freely upon the mandrel. The casing is then returned to the starting position (Fig. 3). By means of the ramp 22, the casing at the end of the 30 return stroke is brought to a gradual stop in the same manner as in forward movement. The pipe 17 hangs on the mandrel 9 and the core 18 is mechanically withdrawn from the head of the pipe. The mandrel 9, 35 after discharging the pressure water, is brought to rest with its rollers 10 on the swivel plate 11 and is swung out of the plane of the drawings. The pipe may now be taken off the mandrel, and the latter swung 40 back into working position. While the casing is at the right-hand end (Fig. 2) the casting tube 6 may be turned on its axle on the support 4 by means of roller 35, and replaced by a second, third, etc. casting tube, 45 the newly attached tube 6 being each time swung back into working position. When the casing is returned, therefore, a new casting tube is in readiness for the next operation. The process may then be continued 50 uninterruptedly.

In place of the casting tube a spraying device of any desirable construction may be attached to spray or underface the casting mould with some desirable material (for instance such as might be suitable for softening the iron). The desired material will, of course, be placed in the container 1 so that it may be distributed therefrom in the interior of the casting mould by the spraying device. Of course during this performance the casing must run idly backwards and forwards through one cycle of the operation.

The provision for interchanging the casting tube has the advantage that it can be

cleaned at leisure from cinders and iron deposits without interrupting the process of manufacture. In addition to that, the casting tube may be heated to any required temperature. The use of the casting tubes provides the additional advantage of eliminating oxidation of the melting material. The removal of the red hot tube also considerably prolongs the life of the casting mould because it is not submitted to continual one-sided effect and wear of the heat. In fact, generally speaking, with this machine almost all the work is accomplished by mechanical processes so that the demand upon manual help is restricted to a minimum. A further 70 advantage of the machine is that innumerable pipes can be turned out with one and the same core, while hitherto the cores made of sand had to be renewed for every pipe, and also had the disadvantage of breaking 80 during the casting. The horizontal arrangement of the casting tube no longer necessitates the sloping position in other machines. Of special advantage is the automatically established co-relationship between the feed 90 of molten metal and the motion of the casting 14. The valve 42 is so constructed that it is normally held open, the valve stem projecting upwardly into the path of the ramps 21, 22. At the beginning of the forward 95 movement, when the pressure fluid is admitted to the left end of the press, the valve stem is, as has been previously pointed out, pressed down by the ramp 22 to almost close the valve 42. The rate at which the fluid 100 can flow out is, therefore, very small and the rate of motion of the piston is correspondingly small. This rate of motion will continue until the horizontal surface of the ramp has passed the stem and the latter is allowed to rise along the inclined 105 surface permitting the valve to open. The rate of outflow of the fluid therefore increases with the gradient of the incline and then reaches full value.

The length of the horizontal portion and the incline are empirically determined to bring about perfect casting action. The arrangement is such that when the motor 31 is set into operation, the stopper 2 is lifted 115 and the control valve 19^a is set at the same time. The length of the time for slowly moving the piston, which corresponds to the length of the horizontal surface of the ramp 22, together with the rate of acceleration, which corresponds to the incline of the ramp 22, are so chosen that the molten metal has time to travel through the casting tube 6 and fill out the head of the mould space, 120 without excess or insufficiency of metal. The combined horizontal and inclined portion of the ramp 22, generally, represents a mathematical curve which is a function of various factors such as length of the path of travel 125 of the molten metal, resistance of path, pres- 130

sure of fluid, effective valve opening when the valve 42 is nearly closed, etc. The feed of the metal and the motion of the casing 14 are thus interdependent, whereby absolute uniformity of the casting operation is obtained.

5 The action of the ramp 21 at the end of the forward operation is equally important, inasmuch as the gradual stopping avoids 10 shocks and jars which would affect the condition of the molten metal before it has time to solidify.

15 The valve 42 at the beginning of the forward stroke and at the end of the rearward stroke throttles the outflow of the fluid from the press and at the end of the forward stroke and the beginning of the return stroke throttles the admission of the pressure fluid into the press.

20 The significance of the reduced speed of the mould at the end of the casting operation is as follows:

25 After the casting operation is completed, the metal cools and shrinks as is well understood. It would then come to rest upon the bottom surface of the mould 15, while moving away from the top surface and also from the sides. The heat transfer from the hot pipe to the mould would thus be concentrated at the narrow zone of contact at the bottom. However, when the mould 15 is not allowed to come to rest but is rotated at a small speed, the heat transfer cannot do any damage to the mould.

30 It is understood that the relative motion between the casting tube and the mandrel and the mould 15 may be effected by holding the casing 14 stationary and moving the casting tube and the mandrel respectively.

35 I claim:

1. A machine for manufacturing piping and the like by centrifugal casting having, in combination, a rotatable casting mold, a casting tube of substantially the same 45 length as the mold having a laterally directed opening, means whereby molten metal is adapted to be forced under pressure into the casting tube and, through the opening, into the casting mold, means for rotating the casting mold, and means for effecting relative longitudinal movement between the casting mold and the casting tube during the rotation of the mold.

50 2. A machine according to claim 1 including a support for the casting tube, constructed and arranged to permit swinging of the latter out of its normal position.

55 3. A machine according to claim 1 including a support for the casting tube, constructed and arranged to afford removal of the casting tube and substitution of another tube therefor.

60 4. A machine of the character described, comprising a rotary casting mold, a casting tube and a mandrel disposed on opposite

sides of the mold and substantially in axial alignment therewith, means for moving the mold, the casting tube and the mandrel relatively to one another so as to position either the casting tube or the mandrel within the 70 mold and means for imparting vertical movement to the mandrel whereby the latter may be raised to freely support the pipe casting.

5. A machine according to claim 4 including a support for the mandrel, constructed and arranged to permit swinging of the latter out of its normal position.

6. A machine for manufacturing piping and the like by centrifugal casting, comprising, in combination a casting tube disposed in substantially horizontal position, means for forcing molten metal under pressure through the casting tube, a casting mold, means for revolubly supporting the casting mold and means for moving the said supporting means to move the casting mold concentrically with the casting tube toward and away from the latter.

7. A machine according to claim 1, including a core for the mold, comprising a plurality of segments separated by radial slits, yielding material in the slits and resilient means for yieldingly holding the segments and the material together.

8. Machine as defined in claim 7 in which the yielding material has the form of combustible strips adapted to carbonize under the conditions of use.

9. Machine according to claim 1 in which the means whereby the molten metal is adapted to be forced under pressure into the casting tube comprises a container and a vertical conduit between the container and the casting tube.

10. Machine according to claim 9 in which the said conduit is separate and detachable from both, the casting tube and the container.

11. Machine according to claim 10 in which the conduit is composed of a plurality of sections whereby the height of the conduit may be adjusted.

12. Machine according to claim 1 including a container, a vertical conduit between the container and the casting tube, said conduit being detachable at its lower end from the casting tube, and a valve stem extending through the container and the conduit to the casting tube for controlling the flow of metal, the casting tube defining a valve seat for the valve stem.

13. In apparatus of the class described, the combination of a casting tube disposed in substantially horizontal position, a casting mold, means for revolubly supporting the mold, mechanism for horizontally moving the mold supporting means toward and away from the casting tube and in substantially concentric relation thereto, means for

controlling the flow of metal through the casting tube, means for controlling the said mechanism and means moving with the casting mold and cooperating with the means for controlling the said mechanism for automatically effecting a period of slow motion of the mold at the beginning and at the end of each stroke.

14. In apparatus of the class described 10 the combination of a casting tube in substantially horizontal position, a casting mold, a support therefor, means for revolving the mold upon the support, a hydraulic press for moving the support toward and 15 away from the casting tube in substantially concentric relation thereto, said press including a conduit and valve mechanism for alternately feeding pressure fluid to the opposite ends of the press cylinder, a control 20 valve in the conduit at one end of the press cylinder, ramps projecting from the said support at both ends thereof, the said control valve having a valve stem extending into the path of movement of said ramps, 25 and the ramps and the stem being so correlated that the stem is depressed and held in depressed condition to decrease the effective valve aperture during predetermined parts 30 of the movement of the said support at the end of each stroke.

15. In apparatus of the class described, a casting mold mounted for horizontal movement, a hydraulic press for moving the mold, a valve near one end of the press cylinder for controlling the inflow and the outflow of the pressure fluid from said end, the valve being normally open and having a stem projecting outwardly from the valve casing, and a ramp at each end of the mold, 20 said ramps being disposed to be in contact with the stem at the beginning and the end of each stroke of the mold and being shaped

to define an inclined portion adapted to effect a gradual movement of the valve between "entirely open" position and "nearly closed" position, and a substantially horizontal portion adapted to maintain the valve in "nearly closed" position during a predetermined part of each stroke.

16. In apparatus of the class described, 50 the combination of a revolvably mounted casting mold, a horizontally disposed casting tube, means for moving the casting mold and tube relatively to each other in concentric relation, and means operative at will to revolve the casting mold at two different speeds, a relatively high speed for the casting operation and a low speed at the end of the casting operation to prevent the tubular casting from coming to rest upon the mold.

17. In apparatus of the class described, 55 a casting mold mounted for horizontal movement, a hydraulic press for moving the mold, a valve for controlling the flow of pressure fluid for operating the press and means movable with the mold for acting upon the valve to automatically vary the effective valve aperture at predetermined points along the path of movement of the mold.

18. In apparatus of the class described, a casting mold mounted for horizontal movement, means for moving the mold, means for controlling the said moving means and means movable with the mold for acting upon said controlling means to automatically vary the rate of motion of the mold at predetermined points along the path of movement thereof.

In testimony whereof, I have hereunto 80 subscribed my name this 26th day of February, 1923.

FERNANDO ARENS.
